UNITED STATES PATENT OFFICE.

WARREN D. SKELTON AND CHARLES H. HAYES, OF THERMOPOLIS, WYOMING.

SPARK PLUG.

Application filed July 19, 1921. Serial No. 485,915.

To all whom it may concern:

Be it known that we, WARREN D. SKELTON and CHARLES H. HAYES, citizens of the United States, residing at Thermopolis, in the county of Hot Springs and State of Wyoming, have invented certain new and useful Improvements in Spark Plugs, of which the following is a specification.

This invention has for its object to provide a strong, durable and leak proof spark plug, and also one which is simple and inexpensive in construction, the parts employed being few and capable of being readily assembled.

15 The invention also has for its object to provide a spark plug having a novel and improved insulating core for the main center electrode, together with other novel and improved features of construction to be described in detail hereinafter.

In order that the invention may be better understood, reference is had to the accompanying drawing, wherein—

Figure 1 is an elevation of the plug, and 25 Figure 2 is a central section thereof.

Referring specifically to the drawing, the body of the plug is composed of two axially aligned sections 5 and 6, the former being a metallic base shell having a reduced and 30 screw-threaded end portion 7 so that it may be screwed into the spark-plug opening of the engine cylinder. The section 6, which is at the outer end of the plug body, is made of fiber or other suitable non-conductive material. The cylinder end 7 of the plug is 35 fitted with the usual side electrode 8 which has a lateral bend to terminate adjacent to the cylinder end of the main central electrode rod 9 of the plug.

40 The end of the plug section 5 to which the section 6 is connected has a reduced central rearward extension 10 which is externally screw-threaded, and the section 6 has a screw-threaded opening 11 of corresponding 45 diameter so that it may be screwed on said extension. Between the outer end of the extension 10 and the opposite end of the opening 11 is interposed a gasket 12.

The extension 10 produces a shoulder 13 50 on the outer end of the section 5, opposite which shoulder the inner end of the section 6 is located, said shoulder having an inward bevel or slope, and the end of the section 6 being correspondingly beveled. Between 55 the shoulder 12 and the inner end of the section 6 is interposed a gasket 13a.

The interior of the section 5 contains a core 14 of non-conductive material through which the electrode 9 passes and in which it is rigidly embedded. This core is flush 60 with the cylinder end 7 of the section 5, and the electrode 9 protrudes therefrom to terminate adjacent to the side electrode 8. The bore of the section 5 containing the core 14 is reduced in diameter near its upper end 65 to form a shoulder 15, and the core is correspondingly shouldered to abut against this shoulder.

The electrode 9 also passes through the fiber section 6 of the plug body to protrude 70 from the outer end thereof, it being here threaded to receive a nut 16, with a gasket 17 and a washer 18 interposed between the nut and the end of the section 6. That portion of the electrode 9 which is embedded 75 in the core 14 has a lateral bend or offset 19, and the threaded portion of the electrode also extends part way into the core, whereby the electrode is firmly held in the core.

The insulating core 14 is formed of a 80 plastic composition which is a non-conductor of electricity, heat and moisture, and which is capable of successfully withstanding severe shocks from the compression and explosions in the cylinder. The electrode 9 is 85 placed in a mass of this composition before it has set, and the mass is forced into the interior of the section 5 until the same, as well as the extension 10, are completely 90 filled, and while under pressure the mass is heated until it becomes dry and hard, whereupon it adheres firmly to the interior of the section 5 and to the embedded electrodes. The core is flush with the cylinder end 7 of the section 5, producing here a 95 smooth surface which can be easily cleaned, and which does not permit oil and carbon to collect upon and around the electrodes 8 and 9. The compressions and explosions in the cylinder have a tendency to keep the plug 100 end clean of carbon and oil.

The outer section 6 of the plug body is made in one piece of condensed vulcanized fiber, or other suitable material which is a non-conductor of electricity, heat and moisture, and 105 is capable of being screw-threaded for connection to the part 10 as hereinbefore described. The purpose of the section 6 is to prevent cracking of the core 14 when hot, by moisture striking it. When a spark plug 110 is equipped as an exposed porcelain, the latter frequently cracks when hot if rain

or other moisture splashes against the same. This trouble is entirely eliminated by enclosing the core 14 as shown. The section 6 also prevents damage of the core 14 when 5 changing plugs. Plugs having an exposed porcelain very frequently are damaged by the wrench or other tool slipping and striking the same.

We claim:

- 10 A spark plug comprising a metallic shell having its upper end provided with a reduced and externally threaded neck and an annular shoulder about the base of the neck, the walls of the neck being projected 15 inwardly to provide an internal abutment shoulder, a protecting body of waterproof insulating material having a pocket lead-

ing from its lower end and having threaded walls for engaging the threads of said neck to removably retain the body upon the neck 20 with its inner end engaging the external abutment shoulder about the base of the neck, a central electrode extending longitudinally through said shell and having a threaded upper end portion extending 25 through said body and beyond its upper end, insulating material filling the interior of said shell about said electrode, and fastener means screwed upon the extended upper end of said electrode. 30

In testimony whereof we affix our signatures.

WARREN D. SKELTON.
CHARLES H. HAYES.
